UNITED STATES PATENT OFFICE

CARL B. CHANDLER, OF HAVANA, ILLINOIS

IGNITION DEVICE FOR FUEL BURNERS

Application filed April 18, 1925. Serial No. 24,042.

This invention relates to ignition devices for oil burners.

The object of the invention is in the provision of a spark ignition device for domestic oil burners.

Another object of the invention is in the provision of spark ignition mechanism utilized in connection with a domestic oil burner of the so-called revolving cup type, said spark ignition mechanism being located in connection therewith in a manner to automatically prevent the accumulation of carbon.

Still another object of my invention is in the provision of a spark ignition mechanism for the revolving atomizer type of domestic oil burner, said spark ignition mechanism being fashioned in such manner as to cause almost instantaneous ignition of the atomized fuel mixture upon commencement of operation of the burner.

A further object of the invention is in the provision of spark ignition mechanism for the revolving atomizer type of domestic oil burner, wherein an electrode is disposed adjacent the rotating atomizing cup in a manner to prevent the accumulation of carbon thereon.

A still further object of the invention is in the provision of a spark ignition mechanism for the revolving atomizer type of oil burner, wherein the sparking device co-operates with the atomizing mechanism to cause substantially instantaneous ignition of the projected fuel mixture.

Yet a further object of the invention is in the provision of a spark ignition device for use in connection with the well known domestic oil burner and automatically operated mechanism for withdrawing the spark ignition device away from the combustion area.

Other objects of my invention will appear in the following specification taken in connection with the annexed drawings, in which—

Fig. 1 is a diagram of the electrical circuits;

Fig. 2 is a detail showing in side elevation of the spark ignition mechanism;

Fig. 3 is a plan view of Fig. 2, taken on the lines 3—3;

Fig. 4 is a detail showing of the float or timing element;

Fig. 5 is a side elevation in broken section, 55 of the fuel burner and fuel supply means; and

Fig. 6 is a cross-sectional view on the line 6—6 of Fig. 4.

Referring to the drawings, I have disclosed 60 a domestic oil burner of the so-called rotary atomizer type, and although my spark ignition device, as far as the automatic mechanism for withdrawing same from the combustion area is concerned, might be applied 65 as well to any of the well known types of oil burners, nevertheless, my present spark ignition mechanism is peculiarly adapted to the present disclosed type of burner.

Before continuing the description, it might 70 be well to say that the prior art discloses spark ignited domestic oil burners with various locations of the spark plug to the discharged fuel mixture.

Applicant has also utilized spark plug 75 mechanism for igniting the projected fuel mixture in the type of oil burning device disclosed in the drawings.

It was to overcome the difficulties that attended the ordinary use of a spark plug to 80 ignite the discharged fuel mixture that prompted the present spark ignition device.

Prior to the development of the present structure, applicant, as did other manufacturers, projected electrodes of a sparking device into the path of the fuel mixture that is discharged tangentially from the rotary atomizing cup.

The above mechanism ignited the fuel mixture, it is true, but not as quickly as was desired, nor did such location of the spark prevent accumulation of carbon and hence necessity for servicing, continually, this part of the burner. It might be said at this time, 90 that although a carbon deposit on a spark plug exposed to the combustion area would be burned off during the burning operation, nevertheless any accumulation of liquid fuel upon the sparking device, when exposed to 95 the tremendous heat in the combustion chamber, 100

ber and not during the burning action, would result in carbon. It was to overcome this carbon deposit as well as to increase the efficiency of the ignition medium that sponsored the following mechanism.

Inasmuch as the present application is directed to the ignition mechanism, only a general description will be given of the fuel burning device which is descriptive of a well known class of domestic oil burners.

The operative portions of the present burner are assembled as shown, within the combustion chamber of any conventional furnace. A hearth 10, is suitably supported in the combustion chamber of the furnace and has an opening therein through which a rotary atomizing cup 11, of the burner projects. This atomizing cup 11 has a fuel feed means 12 connected thereto, adapted to discharge the fuel into a recess 13, at the base of the cup, the rotating action of this cup inducing a flow of air through the opening 14, said air assisting in the atomizing action which takes place mainly adjacent the outer rim of the cup, said atomizing action being augmented by the air circulating at the edge of said cup. Means for rotating the cup 11 is provided in a vertically disposed shaft 15, suitably supported in a formal support 16, and bearing 17. A formal electric motor 18 is adapted to drive the shaft 15, through the friction connections 19 and 20. Also assembled in an operative position with relation to the electric motor, is a conventional pump 21, adapted upon operation of the motor to draw fuel from a supply tank 22, through appropriate lead 23, and deliver fuel through the above mentioned tube 12, to the rotary atomizing cup. A needle valve 24, in the delivery tube 12, provides means for adjusting the fuel feed.

Another adjustment mechanism for the burner is provided in an adjustable supporting screw and bracket mechanism 25, for the electric motor, making possible an option speed of the rotary cup, due to the varying of the position of the friction elements 19 and 20. Fuel withdrawn by action of the pump 21 that is in excess of the amount required by the fuel pipe 12, is returned through the pipe 26, to the main fuel supply tank 22.

The spark ignition mechanism which forms the basis for the present application, will be described in detail following a description of the timing mechanism therefor.

It is desirable that the ignition means operate merely upon a commencement of the operation of the burner, and then but temporarily. To accomplish the above result, I have provided a mechanically acting means controlled by the fuel flow, made up of the following elements.

Referring to Figs. 4 to 6 is shown a container 32, located in the return line 26, said container being suitably supported by

bracket 33, as well as the inlet and outlet pipes thereto, said devices being both in the above described return fuel line 26. The container 32, has a fuel inlet 34, discharging fuel during the operation of the device, into a passageway 35. Means for restricting the main outlet from the passage 35, is provided in an adjustable screw member 36. Another outlet from this passage 35 is provided in a similarly controlled means by adjustable screw 37, regulating the passage of the fuel into a float chamber 38, wherein is disposed a formal float member 39, having a stem 40, projecting through the upper side of the container 32. An overflow from the float chamber is shown at 41, said overflow connecting with the main outlet 42, as well as the fuel discharge normally passing through the main opening controlled by the adjustable screw 36. The projecting end of stem 40, of the float 39, has a loose connection 43, with a movable electrical contact arm 44. This contact arm 44, influenced by the action of the float member, is adapted to operate a mercury bulb having the contact points 45 and 46. This mercury bulb is adapted to control the circuit of the sparking device, the operation of which is now to be described.

My present spark ignition device includes a single electrode 50, disposed in a vertical manner adjacent the atomizing cup 11, the upper end of which is bent at a point slightly above the lower edge of the atomizing cup, and the remaining short and sharpened end of the electrode projects downwardly to a point adjacent the rim of the said lower edge of the atomizer. This sparking end of the electrode 50 is disposed not radially but in an angular relationship to the radius of the rotary atomizing cup and is set for a sparking gap between the tip thereof and the edge of the rotating cup of about $1/8$ of an inch. Direction of rotation, as indicated by arrow in Fig. 3 of the drawings, shows that the location of the electrode above described is such that the tangential discharge of fuel mixture from the swiftly moving atomizer is such that the spray therefrom will strike the electrode in a manner to be concentrated or enriched at the spark gap. This concentration or enriching of the fuel mixture is due to the angular relation between the electrode and the radius of the cup and the slight elevation of the bent portion thereof, above the edge of the rotating cup. As a matter of fact, the actual spark gap is slightly below the tangential spray, but this assists in quick ignition for the reason that the projecting fuel mixture, after striking the bent portion of the electrode, is forced downwardly towards the spark gap where it is concentrated or enriched and ignited at a point out of the main blast.

It is obvious that the revolving cup forms

the ground for the spark. The electrode 50 has a removable mounting 51, namely a brass friction strip, with the main electrode 52 to permit ready removal and assembly.

- 5 The electrode 52 is bent to permit possible and practical insertion in the housing member 53, said electrode being embedded in a formal porcelain insulator 54, which is retained in a supporting member 54', the same 10 being slidably mounted in the housing 55. The bending of the electrode 52 at the point 50^a is to prevent the possible gravitation of fuel into the housing 53 and hence carbonizing the plug. The housing member is bracketed as at 56 to the pedestal 57 of the burner and is open at the end to permit insertion therein of the plug, there being a slot 58 at the upper end portion to permit insertion of the bent portion of the electrode as well as 15 a slight reciprocatory movement. Means for closing the upper end of the housing 55, after insertion of the plug, is provided in a cap 59. Proper location of the spark plug within the housing and means for guiding 20 the movement thereof is provided in a slot 60 in the housing 55 and a set screw 61 adapted to be slidable in the slot as well as to be inserted in the portion 54 of the plug from the outside. 25
- 20 Securely attached to the wire connecting end 62 of the spark plug is a connecting member 63, said member 63 being attached by means of the insulated portion 64 with the core 65 of a solenoid 66. A bracket 67 is provided for attachment of the solenoid to the pedestal. 30

The mechanical means for timing the spark has already been described, and the electrical connections for the ignition mechanism are 40 as follows: Wires 68 and 69 carry the line voltage to a formal transformer 70. From the low voltage side of the transformer 70 is the grounded wire 71, the other side of the low voltage circuit 72 passing through a formal spark coil 73, the above described mercury bulb containing the contact points 45 and 46, and finally being connected at the point 62 with the peculiar spark plug or ignition member. As previously described, 45 the ground for the electrode 50 is the rotating cup.

The mechanism controlling the operation of the solenoid and hence the reciprocation of the sparking member is provided partly 55 in the float mechanism previously described. In other words, the movement of the lever 40 on the float member operates upon the opposite side a similar mercury bulb having the contact points 74 and 75 therein. Similarly, movement of the float operates, after a 60 determined time, to open the electrical circuit through the mercury bulb. The electrical circuit adapted to operate the solenoid is as follows: The high voltage from the line is 65 carried over the wires 76 and 77 to a second

transformer 78. On the low voltage side of the transformer 78, one wire 79 leads to the mercury bulb which is adapted to be operated by the float mechanism and the other wire 80 is carried through the solenoid 66 and finally to the mercury bulb.

The operation of the device is as follows: Upon commencement of operation of the burner, an atomized fuel mixture is projected tangentially from the rim of the rotating cup. This initial operation of the burner results in the completion of the electrical circuit to the solenoid as well as completing the electrical circuit to the sparking member. The action of the solenoid, due to the upward movement of the core therein, raises the sparking mechanism, and hence the electrode 50, to a point adjacent the rotating cup of the burner. Simultaneous completion of the electrical circuit to the electrode results in a continuous spark across the gap between the end of the electrode 50 and the edge of the rotating cup. The fuel mixture tangentially discharged from the rim of the rotating cup is projected slightly upward and due to the peculiar location of the electrode, only the raised portion thereof lies in the path of the mixture, with the result that the fuel mixture striking the electrode is forced downwardly to the gap, across which a spark is continuously jumping. This abrupt stopping of a portion of the fuel mixture, and the consequent movement of same to the ignition point results in a rich mixture for ignition purposes, and hence, an almost instantaneous ignition of the atomized fuel. It might also be said that the fact that the spark itself is just below the discharging fuel mixture, rather than directly in the cone of same, prohibits the blowing out of the initial ignited fuel mixture, and thus assists quick ignition.

Once the burner is ignited, means has been provided for withdrawing the electrode 50 from out the combustion area. This mechanism is timed similarly to the timing of the spark ignition, namely, by the float mechanism. After a determined time, or more specifically, when the float reaches an elevated position, the two mercury bulbs containing the respective contacts 45, 46, 74 and 75, are moved to a position whereby the electrical circuit is opened in the bulbs, thus cutting off the electrical circuit to the sparking device, as well as de-energizing the solenoid. This de-energizing of the solenoid results in a dropping of the core and consequent downward movement of the electrode 50, from out the combustion area.

The reason for the withdrawal of the electrode after ignition is to prevent almost entirely the accumulation of carbon upon same. While the electrode projects into the cone of discharging fuel mixture, a small portion of said mixture is deflected from the combustion area, collecting upon the electrode 125

and gravitating downward thereon. Carbon results from the exposure of unatomized fuel to intense heat, hence, to prevent this accumulation of carbon, as well as the continued exposure of the electrode to the direct flame of the burner, the above described means for withdrawing same has been devised, and it might also be stated that the washer 81 is attached to the electrode at a point a short distance from the sparking end thereof, the same being adapted to catch any unatomized fuel that collects upon the electrode, and to suspend same so closely to the combustion area that it will be entirely burned off.

Again, with respect to the matter of carbon, applicant's sparking device is absolutely prevented from collecting carbon at the sparking point, due to the fact that it is located, during the ignition period, adjacent the revolving edge of the atomizing cup and hence is automatically cleaned in case carbon has collected for some unforeseen reason.

What is claimed is:

1. In a fuel burning device, in combination, a combustion chamber, means for projecting an atomized fuel mixture therein comprising a rotating cup member, a sparking member for igniting said fuel mixture, including a sparking point located adjacent the periphery of the rotary cup member and at a spaced interval therefrom, a rearwardly extending portion disposed in the path of the fuel mixture and adapted to divert a portion thereof into the sparking gap in a manner to enrich the mixture at the sparking point, and a cup member disposed a substantial distance below the sparking member in a manner to trap the unburned condensed fuel mixture and to hold the same in close proximity to the ignited fuel mixture.

2. In a fuel burning device, in combination, a combustion chamber, means for projecting an atomized fuel mixture therein, comprising a rotating cup, means for igniting said fuel mixture including an electrode fashioned to provide a spark gap between the contact point thereof and the periphery of the rotating cup, and means controlled by the operation of the burner for advancing the electrode into the combustion area upon the commencement of operation of the burner and automatically controlled mechanism for withdrawing same from the combustion area after a sufficient period for ignition.

3. In a fuel burning device, in combination, a combustion chamber, means for projecting a fuel mixture therein, comprising a rotating cup member, spark ignition mechanism for igniting said fuel mixture, said mechanism including an electrode located adjacent the rotating cup in such manner that said cup forms a ground for the electrode, a mixture diverting member formed as a part of the electrode, said member being elevated above the rotating cup and in the path of

the fuel mixture in such manner as to project a portion thereof into the spark gap to enrich the mixture at said point.

4. The combination with a fuel burner, of electrically power driven means for discharging a fuel mixture into a zone of ignition, a combustion chamber, spark ignition mechanism and means automatically controlled by the operation of the burner for advancing and withdrawing said spark ignition mechanism from the zone of ignition, said means including electrically operated mechanism controlled by the operation of the electrically power driven means.

5. In combination, with an oil burner, of electrically power driven means for discharging a fuel mixture into a zone of ignition, a combustion chamber, spark ignition mechanism and means comprising mechanism automatically controlled by the operation of the burner for advancing and withdrawing said spark ignition mechanism from the zone of ignition.

6. In combination with an oil burner, of power driven means for discharging a fuel mixture into a zone of ignition, a combustion chamber, an ignition member, and means comprising mechanism automatically controlled by the operation of the burner for advancing and withdrawing said ignition member from the zone of ignition.

7. In combination with an oil burner, of electrically power driven means for discharging a fuel mixture into a zone of ignition, a combustion chamber, spark ignition mechanism and means comprising mechanism automatically controlled by the operation of the burner for advancing said spark ignition mechanism into the zone of ignition, and mechanism automatically controlled by the operation of the burner for withdrawing said spark ignition mechanism from the zone of ignition.

8. In a fuel burning device, in combination, a combustion chamber, means for projecting a fuel mixture therein comprising a rotatable cup member, power means for driving said cup member, a friction connection between the cup member and the power means, and spark ignition mechanism comprising an electrode disposed adjacent the edge of said cup member in a manner to form a spark gap therebetween, said electrode having a portion thereof disposed in the path of the projected fuel in a manner to divert a portion of the fuel mixture into the spark gap.

In testimony whereof, I have hereunto subscribed my name.

CARL B. CHANDLER.
